(57) **CLAIM**

The ornamental design for a domed and dimpled golf ball marker, as shown and described.

DESCRIPTION

FIG. 1 is a perspective view of a domed and dimpled golf ball marker in accordance with the new design;

FIG. 2 is a top plan view of FIG. 1;

FIG. 3 is a front elevational view of FIG. 1;

FIG. 4 is a side elevational view of FIG. 1;

FIG. 5 is an exploded perspective view with the dome removed for clarity if illustration;

FIG. 6 is a top plan view of FIG. 5;

FIG. 7 is a perspective view of a second embodiment of the domed and dimpled golf ball marker in accordance with the new design;

FIG. 8 is a top plan view of FIG. 7;

FIG. 9 is a front elevational view of FIG. 7; and,

FIG. 10 is a side elevational view of FIG. 7.

The broken lines shown on FIGS. 1-10 form no part of the claimed design.

1 Claim, 10 Drawing Sheets
